UNITED STATES PATENT OFFICE

94,774

DESIGN FOR A CLOCK CASE

Shepard Pond, Winchester, Mass., assignor to
General Electric Company, a corporation of
New York

Application December 15, 1934, Serial No. 54,436

Term of patent 14 years

To all whom it may concern:

Be it known that I, Shepard Pond, a citizen of the United States, residing at Winchester, county of Middlesex, State of Massachusetts, have invented a new, original, and ornamental Design for a Clock Case, of which the following is a specification, reference being had to the accompanying drawing, forming a part thereof. Fig. 1 is a front view of a clock case showing my new

design, and Figs. 2 and 3 are respectively side and top views thereof.

I claim:

The ornamental design for a clock case as shown.

In witness whereof, I have hereunto set my hand this fifth day of December, 1934.

SHEPARD POND.
